UNITED STATES PATENT OFFICE.

CASPER SCHAEFER, OF SAG HARBOR, NEW YORK, ASSIGNOR TO FAHYS
WATCH CASE COMPANY.

DESIGN FOR A WATCH-BOW.

No. 38,551.

Specification for Design.

Patented May 7, 1907.

Application filed April 3, 1907. Serial No. 366,233. Term of patent 14 years.

To all whom it may concern:

Be it known that I, CASPER SCHAEFER, a citizen of the United States, residing at Sag Harbor, in the county of Suffolk and State of New York, have invented a new, original, and ornamental Design for Watch-Bows, of which the following is a specification, reference being had to the accompanying drawing, forming part thereof.

The figure is a plan view of a watch bow, showing my new design.

I claim:

The ornamental design for a watch bow, as shown.

CASPER SCHAEFER.
